UNITED STATES PATENT OFFICE.

WILLIAM C. STARKEY, OF MANSFIELD, OHIO.

ELECTRIC LIGHTING.

1,181,550.

Specification of Letters Patent.

Patented May 2, 1916.

Application filed May 9, 1910. Serial No. 560,390.

To all whom it may concern:

Be it known that I, WILLIAM C. STARKEY, of Mansfield, county of Richland, and State of Ohio, have invented a certain new and useful Improvement in Electric Lighting; and I do hereby declare that the following is a full, clear, and exact description thereof, reference being had to the accompanying drawings.

10 The object of this invention is to provide means for automatically maintaining the efficiency or candle light of incandescent lamps when the current in the circuit therefor diminishes below a predetermined normal voltage. The invention has been made with particular reference to use in electric cars so that when the current in the circuit diminishes materially below normal, automatically operated means will modify the resistance 20 in the circuit so as to maintain a normal current in the lamp circuit or will cut out enough lamps to leave an average normal current for the remaining lamps, whereby the efficiency of the lamps will be maintained.

The chief feature of the invention consists in the use of a series relay for controlling the current that passes through a lamp circuit or through a part of the circuit. 30 This relay accomplishes its object by cutting out some resistance, and that resistance may be either a lamp or a series of lamps, or a resistance coil, or the like.

The nature of the invention will be understood from the accompanying drawings and the following description and claims.

In the drawings Figure 1 is a diagram of lamp circuits having a resistance coil and a relay for automatically cutting out a resistance coil when the voltage is below normal. Fig. 2 is a diagram of the lamp circuits with a relay arranged to cut out a portion of the lamps. Fig. 3 is a diagram showing the relay mounted in connection with one lamp so as to cut out that lamp when the voltage is below normal. Fig. 4 is a side elevation of one lamp and relay. Fig. 5 is a central vertical section through the relay for the lamps shown in Fig. 4.

50 In the diagram shown in Fig. 1 the current comes in over the wire 10 and passes through a series of lamps 11 and out over the wire 12 through the magnet 13 of the series relay, wire 14, resistance coil 15 to ground at 16. With this arrangement a current is employed having a higher volt-

age than is necessary for the lamps, and that voltage is normally reduced by the resistance coil. The relay is provided with an armature 17 pivoted to an arm 18 and adapted to engage two terminals, one on a wire 19 running to ground, and another 20 running from the wire 14. The magnet 13 and armature 17 are so arranged that the armature will be attracted by the magnet 65 only when there is the excessive current above spoken of. When that current diminishes sufficiently to permit the armature 17 to fall away from the magnet, the latter will connect the wires 19 and 20 so that the current through the magnet and wire 14 will pass out through the armature 17 and wire 19 to ground, and thereby, with a smaller voltage in the circuit, leave to the lamps an average voltage as high as that had before. 70 In other words, the relay has merely short-circuited the resistance which has been reducing the portion of the current going to the lamps.

In Fig. 2 there is no resistance coil 15 but instead, the wire 119 runs from a terminal near the armature through the series of lamps so as to cut off a portion of it. As shown in Fig. 2, one-fifth of the lamps is cut off. A wire 210 runs from the other 85 terminal near the armature to the wire 12. With a normal voltage all the lamps will be efficient, but when the voltage becomes low, the armature 17 will drop and connect wires 119 and 210. Then the current will 90 not pass through the cut-out lamps, but will come in over wire 119, the armature and wires 210 and 12 through the magnet and out to ground over wire 14. Since only four-fifths of the lamps are now in use, there 95 will be an average normal voltage.

Still another and probably a more useful and common form is shown in Figs. 3, 4 and 5. In Fig. 3 the current comes in over wire 10, through some of the lamps 11 to the magnet 13 of the relay interposed in the series of lamps and connected with one lamp 111. Wires 30 connect the lamps and between the connecting wires for three lamps wires 31 and 32 run from the armature terminals so as to short-circuit the middle lamp. When the armature drops down the current is low. Therefore, as shown in Fig. 3, when the current is low the middle one of the five lamps is cut out, but the current passes through the other four, which may get the average voltage. The total candle

power of the four lights left in the circuit is much greater than the total candle-power of the five lights would be if they were all in the circuit on the same total voltage. 5 This is due to the fact that the candle power of any incandescent lamp increases much more rapidly than the voltage. To illustrate; tests by lamp manufacturers show that with lamps having 100% voltage we have 10 100% candle-power while if the voltage is decreased to 90% the candle-power is decreased to only 53%. This explains why the relay in cutting out the one light gives an ultimately better efficiency to the total lighting circuit. 15

The preferable construction of relay adapted for cutting out individual lamps is indicated in Figs. 4 and 5. There is a cylindrical casing 40 which is internally 20 threaded at each end, and the ends 41 and 42 are non-conducting disks that screw into the casing. The end 41 has a screw plug 43 adapted to screw in the usual socket 55 for an incandescent lamp. It is filled with 25 a non-conducting block 44 with a centrally located conducting rod 45 that is connected by a wire 46 with a terminal 47 that extends through the non-conducting block 48 in the socket 49, into which the plug of a lamp 11 30 is adapted to screw. The magnet 13 is located within the casing just described and it is connected by a wire 50 with the plug 43 and wire 51 with a terminal 52 in the end 42. The two terminals 47 and 52 are 35 in position to be engaged by the armature 17 when it drops to the dotted-line position shown in Fig. 5. Then the current which has previously been going through the lamp is short-circuited through the armature 40 from the wire 51 to the wire 46 and said lamp is cut out. When the circuit resumes 45 its normal current, the armature 17 will be drawn back to the magnet and the lamp 11 will be cut in.

45 From the foregoing explanation it is seen that the form of relay shown in Fig. 5 may be used in connection with any number of lamps as desired and will automatically cut out the lamps according to the current in 50 the circuit and they will be cut in upon the resumption of a normal current. The lamp shown in Fig. 3 and the number of lamps shown in Fig. 2 that are adapted to be cut out are something in the nature of resistance 55 and to some extent perform the same function as the resistance coil 15 in Fig. 1, but the former arrangement is preferable because normally there will be more lamps than with the arrangement shown in Fig. 60 1, and the arrangement shown in Fig. 3 is preferable because by having a supply of relays shown in Fig. 5 on hand the number of lamps may be arranged in the manner described to suit even a very reduced condition 65 of the current: that is, so as to cut out

three of the lamps shown in Fig. 3 and leave two lamps which will receive enough current to have the normal efficiency.

The relay herein is a series relay for regulating the current as distinguished from the voltage relay and, therefore the total current which passes through all of the lamps connected in series also passes through the relay. 70

I claim as my invention:

1. In an electric lighting system of the class described, a circuit including a varying voltage source of power and a plurality of translating devices, a shunt circuit around at least one of said translating devices, and a single electrically operating means in series with said translating devices for opening and closing said shunt circuit. 80

2. In an electric lighting system of the class described, a source of power of variable voltage, a plurality of translating devices in series in said circuit, a normally open shunt circuit around at least one of said translating devices, and a relay in series with said translating devices responsive to a predetermined drop in current for closing said shunt circuit to maintain a constant current in the other devices. 90

3. In an electric lighting system of the class described, a circuit including a source of power subject to substantial fluctuations in voltage, a plurality of translating devices in series in said circuit and subject to the fluctuations in voltage producing changes of current therein, and an automatic regulator also in series with said translating devices and responsive to predetermined variations in the current for controlling the current through at least one of 95 said translating devices for maintaining constant the current in the other translating devices. 100

4. In an electric lighting system of the class described, a circuit including a source of power subject to fluctuations in voltage, a plurality of lamps in series in said circuit and also subject to said voltage and to current fluctuations, and means in series with said lamps subject to said current fluctuations for increasing the current in a number of lamps less than the total number thereof. 110

5. In an electric lighting system of the class described, the combination of a source of power subject to fluctuations in voltage, a circuit including a plurality of lamps in series subject to said voltage fluctuations, a regulator comprising an electro-magnet in series and subject to current fluctuations, a lamp normally in said series, and means controlled by said electro-magnet for cutting the regulator lamp in and out of said circuit in accordance with the current fluctuations. 120

6. In an electric lighting system of the class described, the combination of a circuit including a source of power and a plurality of lamps in series and subject to voltage and consequently to current fluctuations, a regulator removably insertible in said circuit and including a lamp adapted to be normally connected in series and a low resistance magnet adapted to be connected 5 in series with said lamps, and means controlled by said magnet in response to said current fluctuations for cutting said regulator lamp in and out of circuit.

7. In an electric lighting system, the combination of a source of power of variable voltage, a circuit including said source of power and a plurality of lamps in series and subject to said voltage and current fluctuations, a low resistance magnet 10 in series, a lamp normally in series, a normally open shunt circuit around said lamp, and means controlled by said magnet in response to a predetermined fluctuation in voltage for closing said shunt circuit to 25 vary the total resistance of and the current in said circuit.

8. In an electric lighting system of the class described, the combination of a source of power subject to fluctuations in voltage, 30 a circuit including a plurality of sockets and

lamps therefor in series subject to the voltage fluctuations and the fluctuations in current, and a regulator adapted to be removably inserted in series between any lamp and its socket comprising an electromagnet 35 and means in connection therewith to cut out of the series circuit the lamp to which it is attached for increasing the current through the other lamps of the series.

9. In a system of the class described, a circuit including a plurality of lamp sockets and lamps therefor connected in series and subject to fluctuations of voltage causing thereby a fluctuation of current, and a regulator removably disposed between a lamp and its socket having a single magnet 40 in series with the lamp and socket with armature contacts and connections therefor with which the armature co-operates to short circuit the lamp to which the regulator is 45 attached when the current is low for increasing the current in the remaining lamps.

In witness whereof, I have hereunto affixed my signature in the presence of the witnesses herein named.

WILLIAM C. STARKEY.
